ALARM SYSTEM

Benjamin Goldstone, Long Beach, N. Y.

Application July 30, 1932, Serial No. 626,444

19 Claims. (Cl. 177—314)

This invention relates to alarm systems. The particular reference had in this connection is to a system of electrical protection for enclosures by which (1) upon an attack made upon the enclosure such that an electrical protective circuit is broken or short-circuited, an alarm will be given; (2) the time when the system is made effective for these purposes will be recorded, as well as the time at which the system is deenergized, and also the time of initiation of an alarm by the system; (3) mechanism locks the main exit from the enclosure after all the other exits have been locked from within the enclosure, the operation of which mechanism is such that passage through such exit is permitted without the initiation of an alarm, but if the mechanism be operated to completely closed position when any of the other exits are not properly guarded, that fact will immediately be indicated by the giving of an alarm; (4) after the permissible passage through the exit, and actuation of the mechanism to barring position, the system will initiate an alarm upon any attempt to tamper with the system or to make an entry through any of the exits including the one barred by the mechanism; (5) the operation of such mechanism effects the printing of the time when such a passage was made through the exit, that is, whenever the locking mechanism is operated to locked or unlocked position; (6) once the system has been energized by fully closing the switch and the locking mechanism, the system continues operative, regardless of the condition of the locking mechanism, as the system may not be defeated by tearing the lines going to the door or by destroying the locking mechanism, an element entirely distinct from the locking mechanism thereafter operating to make the system continuously effective; (7) the locking mechanism is provided with automatic means which, once released, permits the mechanism to function but once without being again released, that is, but one operation of the lock from open to closed, and then to open, position again, will be permitted for a single release of the automatic means; (8) the release of the lock mechanism to permit this single complete cycle is made the function of a coin-controlled mechanism; (9) the locking mechanism, by its operation, effects at least three simultaneous functions; (a) the locking of the main door or exit to prevent access to the interior of the enclosure guarded; (b) the printing of the times at which the system is made effective or at which the door is bolted and unbolted; and (c) the energizing of the entire system for the purpose

of initiating an alarm, and this is true whether a main switch on the panel is closed by a thoughtless operator or not.

The alarm system intended for this purpose generally consists of an electrical conductor strung across portions of the walls of an enclosure through which access might be had to the interior of that enclosure. Current is passed through this conductor, or, in open circuit work, a power source is made available for forcing current through that conductor when an attack is made upon the system. In closed circuit work, current flows continuously through the conductor and energizes a relay which retains in raised position an armature or drop until the energizing current is cut off by interference with the system. When this happens, the drop effects the completion of a circuit, the result of which is the energization of a gong circuit or a circuit of some other similar alarm producing elements for well known purposes.

Where movable closures are provided for exits from such enclosures, a party within the enclosure must be provided with some means for safe passage through one of these exits in order that the alarm shall not be effected until he has completed his passage out of the enclosure. It is an object of the invention to provide means which operates as a lock for preventing opening of such a closure, the lock also having associated with it mechanism to effect the deenergization of the alarm circuit and permit free passage through the exit governed thereby until the lock has been moved to locking position. Thereafter, any interference with the door would cause the initiation of an alarm whether the lock be fouled or even be completely removed from the door. Until the lock has been closed, no alarm can be initiated; passage through the door may take place freely, until the lock has been manipulated to closed position, without danger of a false alarm.

Where stores are under the supervision of employees, as in chain-store operation, it is highly desirable to have some record that the alarm system was actually made effective and also, of course, the times at which the employees opened and closed the premises and thereby made the alarm effective and ineffective. In conjunction with such an apparatus, the time at which an alarm was initiated and the related time at which attention was had to the alarm, with consequent deenergization thereof, is also desirable. For this purpose, the system has incorporated thereinto means for recording the time at which

the lock is actuated to open or closed positions, and also to record the time at which any break or any other interference with the alarm system is caused. It is an object of the invention, 5 in conjunction with apparatus of this character, to provide time-controlled means for positioning printing devices for the purposes indicated and to associate therewith a plunger mechanism control, the action of which will be momentary so that no interference with the continued rotation or operation of the printing device will be caused. The impact will merely be sufficient to effect the imprint on a suitable tape with consequent release of the printing device 10 for further time-controlled rotation.

The property that the locking mechanism, once released, can function only for one complete cycle and then is again made ineffective is utilized in making the releasing means the 15 subject of coin-control.

It is well to understand, at this time, the manner in which these systems function in commerce. Operating and service companies install the systems at much below their actual cost, and 20 thereafter supervise the operation of the system for a definite sum per unit time, as per day, week, month or a like term. Collections, as usual, involve the customary problems, where service has been rendered and the amounts involved are so small as not to warrant any costly 25 collection action. If the patron be made to pay in advance a suitable sum at each time he desires his system made operative, this necessity for enforcing collections is entirely avoided. It is an 30 object of the invention to associate with the lock means to make the locking means inoperative for actuation to locking position unless a suitable check or token be first deposited in a receptacle provided for that purpose, and thereby to make 35 impossible the energization of the alarm system until the proper monetary representative has been assembled with the apparatus.

Other objects of this invention will herein-after be set forth, or will be apparent from the 40 description and the drawings, in which are illustrated embodiments of apparatus for carrying out the invention.

The invention, however, is not intended to be restricted to any particular construction or arrangement of parts, or to any particular application 45 of such construction, or to any specific manner of use, or to any various details thereof herein shown and described, as the same may be modified in various particulars or be applied 50 in many varied relations without departing from the spirit and scope of the claimed invention, the practical embodiments herein illustrated and described merely showing one of the various form and modifications in which the invention 55 might be embodied.

On the drawings, in which the same reference characters refer to the same parts throughout, and in which are disclosed preferred embodiments:

Fig. 1 is an elevational view of a casing having housed therein timing mechanism, a printing device and certain portions of the alarm circuit by which certain of the elements of the invention are effected;

Fig. 2 is a side elevational view, showing a detail of the time printing mechanism;

Fig. 3 is an elevational view of a lock casing constructed to embody certain features of the invention;

Fig. 4 is a vertical sectional view, on the line

4-4 of Fig. 3, illustrating the disposition of the various elements of the lock mechanism;

Fig. 5 is a transverse sectional view, on the line 5-5 of Fig. 3, illustrating details of the coin-controlled mechanism;

Fig. 6 is an elevational view of a portion of the locking and coin-controlled mechanisms, shown in an intermediate position of coin-actuation;

Fig. 7 is a view, similar to Fig. 6, illustrating further operation of the locking mechanism;

Fig. 8 is a diagrammatic view of the alarm circuit, illustrating the incorporation thereinto of the lock and the printing mechanism, the lock casing being shown diagrammatically to illustrate the cooperation of the casing and elements 15 therein with the circuit, and

Fig. 9 is an across-the-line wiring diagram for the circuit.

For purposes of convenience in installation, 20 the relays and other elements of the system may be housed and contained within a casing 10, preferably of metal or any other suitable material. Housing the elements in this manner, and locking the casing against unwarranted access to 25 the parts contained therein, is desirable to prevent interference from within the guarded premises with the operation of the electrical apparatus to be described. Within the casing may be supported a panel 12 upon which is mounted 30 clock-work 14. A spindle 16, driven by the clock-work, causes rotation, through suitable gearing 18, of minute and hour wheels 20 and 22, respectively mounted on the same shaft and permitted 35 relative movement. Dials 24 and 26 are also supported in front of the panel, and hands 28 and 30, one carried by spindle 16 and the other by a suitable spur shaft 32, driven from gearing 18, indicate on the dials the hour and minute at which the wheels are set to print, as will be 40 described. The minute wheel is permitted movement and thus can be used to set both hour and minute wheels and hands, the hands indicating the particular setting.

Also, driven from this spindle, by suitable gearing 45 34, is a spur shaft 36, to which is secured a roll 38. A tape 40, fastened to the roll, is caused thereby to move past the printing point 42, being guided by means of rollers 44 and 46 from a supply roller 48. Suitable friction devices may be 50 utilized for retaining tape 40 in tension in its movement past the printing point.

Assembled directly beneath wheels 20 and 22 is an electromagnet 50 consisting of a pair of solenoid coils 52, retained in spaced apart relationship by a bracket 54 by which they are supported from panel 12. The bracket and a cross-brace 56 at the lower ends of the solenoids form guides for a plunger 58, the lower end of which is secured to an armature 60. Guide pins 62, extending from the armature and extending within the bores 64 of the solenoids, serve to retain the armature in position for movement in a predetermined plane so that an impact head 66, at the upper end of the plunger, may be directed properly toward the tape and wheels 20 and 22. When the solenoids are energized, plunger 58 will be driven upwardly, and cause impact of head 66 against the tape and wheels to make an imprint upon the tape. Suitable inking rollers 68 may 65 be retained in contact with the wheels by means of springs 70 to provide a suitable medium for making legible the imprint on the tape. While the continuous rotation of roll 38 by gearing 34 is illustrated, it is, of course, to be understood that 70 75

any other well-known method of operation may be used.

Suitably disposed within the casing are a plurality of relays 72, 74 and 76. Relay 72 has a pair of armature blades 78 and 80, properly insulated from each other. The armature blades 78 and 80 have individual sets of contacts, the sets being indicated as 82 and 84, and 86 and 88, respectively. The contacts are connected in the circuit in the manner to be described hereinafter. It is to be understood that the particularly disclosed construction of these relays may, for certain elements of the invention, provide an alternative form for use in effectuating the results intended. Each of the relays includes a magnet coil 90, from which armature blades such as 78 and 80 fall away by gravity against contacts such as 82 and 86, when the coil is deenergized. When the coil is energized by current flowing therethrough, the armature blades are raised against such contacts as 84 and 88. If desired, a spring 92 may be provided to assist gravity in bringing the armature blades against such contacts as 82 and 86.

Lock 94 includes a casing 96, shaped to house the elements therein and also, in a suitable instance, to provide prongs 98 for engagement with a suitable strike (not shown), with which will engage the bolt 100 of the lock. Across the upper end of the casing may be extended a plate 102; in this plate, there may be formed one or more spaced apart slots 104. When all the elements of the lock and of the related switching and coin-controlled apparatus have been properly assembled in the casing, and a pair of screws or similar headed protuberances 106 formed on the door or similar member (not shown) with which the lock is to be associated, the large ends 108 of the slots are engaged over the headed portions, after which the lock body is slid downwardly along the door until the bodies of the protuberances are seated within the small ends 110 of the slots. Securing means such as a screw may then be passed through the back wall 112 of the casing to anchor the casing fixedly to the door on which it is to be supported. Such securing means is made accessible through an opening 114 in the front wall 116 of the casing, which opening may be closed and guarded in the manner to be described.

The particular type of locking elements 118 here shown are not intended to be absolutely essential parts of the invention and, therefore, need not be specifically described. The elements should include a means similar to pin 120 for engagement with a lever 122, which pin, by its movement as the elements move to the various positions for locking or unlocking, effects rocking of that lever. In the instance shown here, elements 118 reciprocate; pin 120, for proper cooperation, is secured to, or made an integral part of, the bolt 100 of the elements, and is positioned to engage and be retained within a slot 124 in the end of the lever. The lever is pivoted upon a boss 126 extending from wall 116; as the elements reciprocate, the lever will be caused to oscillate about its pivot as an axis. The lever, through its pivot, is grounded electrically upon the casing; being of metal, it provides a movable electrical connection between the casing and contacts 128 and 130 set in a backing piece 132 of suitable insulating material, retained spaced away from wall 116 to permit access thereto of suitable conductors. In the position shown in Fig. 3, the lever rests upon a dead contact 134, in this case not made a part of any circuit.

Bolt 100 is shown to have a projection 136. Pivoted upon a pin 138 secured to wall 116 is a lever 140, shaped like a reversed "7"; the short arm 142 of this lever, by means of a spring 144, fulcrumed upon a pin 146 extending from wall 116 and anchored at 148 to a plate 149 rigidly associated with the casing so as to engage against the angularly bent arm 150 of lever 140, is forced up against the bolt and tends to engage against the bolt and behind projection 136 and thus to prevent projection of the bolt to locking position. To release lever 140 from this engaged relationship, in order that the locking elements then be able to function both as a lock and also for the purpose of switching the several related circuits into operation, a coin-controlled mechanism 152 is provided.

The coin for the operation of mechanism 152 is associated with the apparatus by insertion through an opening 154, formed through front wall 116. An arcuate passage 156 in a member 158 is in direct communication with opening 154. Member 158 may be made up in any desired manner, as, for instance, as a die casting. This casting preferably is secured to wall 116 so that the arcuate groove 160 together with the wall defines passage 156. The passage is defined in its width to permit only a definite coin 162 to move therein.

Downwardly along the passage from opening 154 and in the wall 164 of the passage, is a slot 166 forming a guideway for a sliding pin 168. By means of a spring 170, fulcrumed at 172 and bearing, at its ends, against one side wall 174 of the casing and against a block 176 integral with or otherwise secured to pin 168, the pin is normally positioned to extend into passage 156.

Carried by a post 178, extending through wall 116 and therein rotatably mounted, and thereby pivotally mounted relatively to member 158 through which post 178 extends, is a plate 180. The manner of mounting the plate will cause its movement to be concentric with passage 156. Encircling pivot post 178 is a spring 182, anchored at 172 to the casing; the normal action of the spring is to compel plate 180 to assume a position in which the plate abuts side wall 184 of the casing. The plate has an embossed portion 186 for fitting within passage 156; the end portion 188 of portion 186 is shaped to conform substantially to the shaping of the coin intended to be deposited in the passage.

On attempted oscillation of the plate by means of a knob 190, disposed upon and secured to the outwardly extending extremity of post 178, if a coin has not been deposited within the passage, portion 186 will halt downward movement of the plate at an intermediate, ineffective stage by engaging with pin 168. If, however, prior to rotation of knob 190, a coin had been deposited, the coin, after seating within the end portion 188, would be forced onwardly by the embossed portion 186 to engage the end of pin 168. By reason of the curvature of the coin, the pin would be cammed out of the passage; the coin would be released then to continue on its way, by gravity, to a suitable receptacle, such as provided by chamber 192. By driving pin 168 out of the passage, the plate is released for further movement as stopping engagement between portion 186 and the pin is eliminated, even after the coin has passed to its receptacle. The depository chamber 192 may be the same as that through which was applied the screw to retain the casing, the opening being sealed by a plate 194, secured, 75

by suitable locking means 196, to front wall 116 to permit only warranted access to that chamber and the locking elements.

Now that the plate has passed the barrier 5 normally interposed by pin 168, a projection 198 from the plate will engage against arm 150, rocking lever 140 to move arm 142 out of engaged 10 relation to projection 136. When the plate has been moved to this position, as shown in Fig. 6, another V-shaped lever 200, pivoted at 202 upon 15 the casing, will, by gravity, and by the action of a suitable spring 204, coiled about the pivot 202 and engaging the lever and the casing, be caused to move downwardly so that its arm 206 will engage against a shoulder 208, formed at the end 20 of plate 180. Plate 180 is thus latched against return until certain further manipulations of the lock elements have occurred.

The lock mechanism is now free for actuation 20 to locking position. By insertion of a key into a suitable receptacle of any particular construction, provided for that purpose, and then turning the key, the bolt will be projected into the associated strike. Projection 136 includes, in 25 addition to the vertical section 210, against which arm 142 abuts when properly positioned, a horizontal shelf 212 upon which another arm 214 of lever 200 extends. As the bolt mechanism is advanced by the key, this shelf engages arm 214, 30 gradually lifting it until, at the extreme of movement of the locking mechanism, arm 206 will be released from its coaction with shoulder 208. Spring 182 will then return plate 180 to its normal 35 relationship in abutment with wall 184.

Lever 140 in the meantime, is retained in lowered position by the bottom of shelf 212; however, with the return of plate 180 to normal position, the relation of lever and locking mechanism is such that, if the locking mechanism be 40 now shifted back to unbarring position, projection 136 will ride free of arm 142, which immediately will be snapped into position behind the projection 136, as shown in Fig. 3, and again prevent any movement of the locking mechanism until a coin has been deposited, or the latching lever 140 released in some other 45 manner.

Lever 122, during movement of the locking mechanism to barring position, has been caused 50 to ride over contacts 128 and 130, and, in movement of the locking elements to unbarring position, to ride back over contacts 130 and 134, in both cases, in the order indicated. Certain results are obtained, by this progressive contacting, 55 in connection with the alarm system to be described.

The circuit, as illustrated, operates on closed circuit principles, although, in certain of its details, the invention may find application for open 60 circuit operation. In this case, a power source 216 of any particular character, such as a battery, is provided. A switch 218, operated by suitable key controlled means, and connected directly with one side of the battery by a conductor 220, 65 may be assembled on casing 10 or at any other suitable point. By another conductor 222, the switch supplies current to a contact post 224 upon a panel 225 within casing 10, to which a section 226 of the house protective circuit 228 is connected. Switch 230, illustrated in this section, 70 is intended to be illustrative of such devices as the circuit breaking spring-switches customarily positioned at closures, and especially at the door upon which lock 94 is assembled.

The other end of section 226 is connected to

another contact post 232 on the panel from which a conductor 234 leads to the core 236 of relay 72. Another conductor 238 returns from this coil to be connected to a contact post 240 upon the panel to which the other section 242 of the house protective circuit is connected. The other terminal of this section is at a contact post 244 on the panel from which a conductor 246 returns to the battery. Therefore, upon closing switch 218, relay 72 is immediately energized to lift armature blades 248 and 250 away from their respective contacts 252 and 254. No other portion of the circuits is so energized unless some defect exist in the house protective circuit. The alarm circuit is not made available for the initiation of an alarm at this time.

Now, when the party closes up his establishment and desires to lock the door upon which lock 94 is assembled, after first closing switch 218, he may pass through the door without the initiation of an alarm since that circuit is not at that time operative since lever 122 rests upon dead contact 134. If, at the time he closed switch 218, there should be any defect in the house protective system, that is, in the circuit 25 energizing relay 72, current would flow from battery 216 through conductor 220, switch 218, conductors 222 and 256, buzzer 258, conductor 260, contact 254, armature blade 250, which, at this time, would be in lowered position, due to de- 30 energization of relay 72, conductor 262, and back to the battery through conductor 246.

Finding the circuit to be in proper order, the party closes the door, inserts his key into the lock, and rotates, or in any other manner, causes 35 movement of, the lock elements so that lever 122 will be caused to move from its dead contact 134, riding over contact 128 and coming to rest on contact 130. Lever 122, by means of conductor 264, is connected to a break-switch 266, normally 40 closing its circuit; but, by means of a push button, or by suitable key-controlled means, being caused to open its circuit. This switch, by a conductor 268, is connected to the battery. When lever 122 advances to contact 128, current will 45 flow from the battery through conductor 268, break-switch 266, conductor 264, lever 122, contact 128, conductor 278, coil 52, and back to the battery through conductor 272. Since this coil is that of the time-recording magnet, armature 60 will be caused to rise and head 66 brought into abutment with the tape and wheels for making an imprint upon the tape.

Now lever 122 leaves contact 128 and passes to contact 130. Current will now flow from the 55 battery through conductor 268, switch 266, conductor 264, lever 122, contact 130, conductor 274, through coil 276 of relay 74, and conductors 278 and 272, back to the battery. Armature blades 280 and 282 are raised by energization of relay 60 74, and are brought into contact with their respective contacts 284 and 286. Relay 74 will now be constantly energized without relation to the association of lever 122 with contact 130 as current now flows from the battery through conductor 268, switch 266, conductors 264 and 288, armature blade 282, contact 286, conductors 290, 222 and 292, armature 280, contact 284, conductor 294 and 274, coil 276, and conductors 278 and 272, back to the battery.

Also, the house circuit will be constantly energized by this arrangement as power will be obtained from the battery through the constantly energized conductor 222. The entire circuit is now energized, and, as will be shown, an alarm 75

will be given in case any interference takes place that breaks the house circuit or crosses any associated portions thereof.

Even if the operator should forget to close switch 218, no ill effects will obtain, as the energization of the circuits will be completed when the lock is moved to closed position. The printing will take place in exactly the same manner, that circuit being wholly independent of switch 218.

10 In like manner, energization of relay 74 will take place independently of switch 218. Immediately upon energization of relay 74 and consequent energization of the house circuit, armature blades 248 and 250 will be lifted clear of their contacts 15 to prevent any possibility of an alarm. In such operation, however, if any part of the house protective system be defective, the alarm apparatus will become effective, as will be shown, and the operator will, of necessity, have to return within 20 the enclosure, discover the nature of the failure of the system, and remedy it before he will be able to set the alarm and leave the premises properly protected. Of course, this will necessitate the deposit of an additional coin in the lock 25 in such case where the coin-controlled operation is utilized. In any case, he will not be able to leave the premises without having been forewarned as to the status of the system.

When a break, or a cross across associated parts, 30 occurs in the house circuit, relay 72 is deenergized, as can easily be understood, current not flowing at all through the circuit because of the break, or being short-circuited from the relay by the cross. In such case, armature blades 248 and 250 rest upon their respective contacts 252 and 254. Buzzer 258 will operate to warn anyone within the enclosure to whom the sounding of alarm 296, which may be located in any desirable position, as, for instance, on the exterior of the building protected, may be inaudible.

For the energization of alarm 296, one path for current from the battery will be through conductor 268, switch 266, conductors 264 and 288, armature blade 282, contact 286, conductors 290 45 and 222. Current also may flow, if switch 218 is closed, directly from the battery to conductor 222. Then the circuit continues through conductor 292, armature blade 280, contact 284, conductors 294, 274 and 298, armature blade 300 of relay 76, its associated contact 302 upon which it will be resting at that time, conductor 304, contact 252, armature blade 248, conductors 306 and 270, coil 52 and conductor 272 to the battery, thus energizing the printing magnet for making an imprint upon the tape as to the time at which interference with the circuit was effected.

Immediately that the printing magnet has been so energized, contacts 308 and 310 are brought together by armature 60, upon which one of 60 the contacts is mounted. Contact 310 may be mounted upon, and preferably insulated from, the cross-brace 56. By association, in this manner, the following circuit is completed. Current now flows from the battery through conductor 268, switch 266, conductors 264 and 288, armature blade 282, contact 286, conductors 290, 222, and 292, armature blade 280, contact 284, conductors 294, 274 and 312, contacts 310 and 308, armature blade 60, conductor 314, coil 316 of relay 76, and conductors 318, 278 and 272 to the battery. Now relay 76 is energized, lifting armature blades 300 and 320, breaking the connection between armature blade 300 and contact 302, and making connection between that armature blade 75 and contact 322.

Relay 76 is now continuously energized by current flowing from the battery through conductor 268, switch 266, conductors 264 and 288, armature blade 282, contact 286, conductors 290, 222 and 292, armature blade 280, contact 284, conductors 294, 274 and 298, armature blade 300, contact 322, conductors 324 and 314, coil 316, and conductors 318, 278 and 272, back to the battery. The breaking of the circuit between armature blade 300 and contact 302 will deenergize coil 52, 10 permitting its armature 60 to drop and be ready for the next operation of the time-recording mechanism.

Simultaneously with the continuous energization of relay 76, the other armature blade 320 15 has made connection with contact 326. The alarm circuit is now energized by current flowing along conductor 268, switch 266, conductors 264 and 288, armature blade 282, contact 286, conductors 290 and 328, armature blade 320, contact 326, conductor 330, alarm 296, and conductor 332, back to the battery.

When the person apprised of the alarm arrives at the enclosure to open it, he must move lever 122 away from contact 130 and over contact 128 in order to open the lock. By such operation, the printing apparatus will be energized and again record the time at which such passage was made. The alarm, however, will continue to ring until push button of switch 266 is 30 manipulated to break the circuit leading from the battery through the holding circuit of relay 74 which also will deenergize the holding circuit of relay 76. At the time this is done, of course, switch 218 may also be opened.

It is to be noted that if vandals should destroy the door and thereby destroy the circuits connected with the lock and lever 122, they would, in no way, make inoperative the alarm circuit.

In such case where the house circuit is found 40 to be defective in either one of its branches, that is, a break is found to be present either in section 226 or in section 242, switches 334 and 336 may be provided. These switches are for cutting out of circuit either one of the house protective sections. They may also be used, in conjunction with switch 218 and buzzer 258, for testing, to determine in which of the sections such break is present. After that defect is located, one of the switches may be left effective 45 so that the circuit may be operative at least for protection against a break until repairs can be made. In outlying regions, assistance sometimes cannot be secured for a considerable period, and the protection to be secured from a single 50 side of the circuit is more desirable than no protection at all.

For instance, if switch 336 be closed, current from conductor 222 will pass along conductor 338, switch 336, post 232, conductor 234, coil 236, 60 conductor 238, post 240, section 242, post 244, and conductor 246, for energization of that side of the circuit. Similarly, the circuit for switch 334 may be used, in which case section 226 will be the protecting portion of the circuit.

Although the invention is illustrated in connection with closed circuit operation, it can be readily understood by those skilled in the art that the invention also has application to open circuit operation.

It is to be understood that the coin-controlled mechanism may be used in conjunction with alarm circuits without the necessity for cooperation either of the time recording mechanism or of the locking mechanism, or both of them. In 75

this relation, the necessity for dealing with accounts has been eliminated. The proprietor determines for himself when he desires protection from this system. Merely by depositing a coin and then manipulating the mechanism, he places in circuit the alarm apparatus; he cannot again initiate operation of the system or use the lock until he has shut down the apparatus and again deposited another coin.

10 The locking mechanism provides a means for governing the passage through an exit and for recording definitely any lawful operation of the lock while, at the same time, controlling such lawful operations by its coin-controlled mechanism.

15 Many other changes could be effected in the particular apparatus designed, and in the methods of operation set forth, and in specific details thereof, without substantially departing from the invention intended to be defined in the claims, the specific description herein merely setting forth 20 illustrative operative embodiments carrying out the spirit of the invention.

25 What is claimed as new and useful is:—

1. In combination with an area to be protected and having exits therefrom, means for guarding the exits against unwarranted passage therethrough, means for initiating an alarm upon attempting to effect passage past the guarding 30 means, one of the exits having a door, means for locking the door against passage therethrough, said locking means, comprising means when actuated to locking position, for making the alarm-initiating means effective, circuit means for indicating the time when the door was locked and the alarm-initiating means made effective, and means to prevent the locking means from being operated through more than a single cycle from unlocked position to a position where it retains the door locked, and thereafter to a position where it is no longer effective to lock the door, whereby, in such cycle, the door may be retained locked for only a single continuous period.

2. In combination with an area to be protected and having exits therefrom, means for guarding the exits against unwarranted passage therethrough, means for initiating an alarm upon attempting to effect passage past the guarding means, one of the exits having a door, means for locking the door against passage therethrough, said locking means, comprising means when actuated to locking position, for making the alarm initiating means effective, circuit means for indicating the time when the door was locked and the alarm initiating means made effective, and means to release the locking means so that, for a single actuation of the releasing means, the locking means may be operated but once through a single cycle from unlocked position to lock and then again unlock the door before the locking means is made ineffective until a further actuation of the releasing means.

3. In combination with an area to be protected and having exits therefrom, means for guarding the exits against unwarranted passage therethrough, means for initiating an alarm upon attempting to effect passage past the guarding means, one of the exits having a door, means for locking the door against passage therethrough, said locking means, comprising means when actuated to locking position, for making the alarm initiating means effective, circuit means for indicating the time when the door was locked and the alarm initiating means made effective, and coin-controlled means to release the

locking means so that, for a single operation of the coin-controlled means, the locking means may be operated to door-locking position and to make the alarm initiating means operative but once as a part of a single cycle at the end of which cycle the locking means is again made ineffective until the operation of the coin-controlled means.

4. In combination with a means of ingress to and egress from an area, means for controlling such ingress to or egress from the area, means for retaining the controlling means in barring position, time recording means, and means for protecting the area against unwarranted ingress to or egress from the area, the time recording means comprising a circuit including an electromagnetic device which, upon such unwarranted passage into or from the area, cause recording of the time of such passage and then cause the protecting means to initiate an alarm, the retaining means, when made operative to retain the controlling means in barring position, having means simultaneously to energize the protecting means.

5. In combination with a means of ingress to and egress from an area, means for controlling such ingress to or egress from the area, means for retaining the controlling means in barring position, time recording means, and means for protecting the area against unwarranted ingress to or egress from the area, the time recording means comprising a circuit including an electromagnetic device which, upon such unwarranted passage into or from the area, causes recording of the time of such passage and then causes the protecting means to initiate an alarm, the retaining means, when operated to position, to retain the controlling means in barring position, having means active during the same operation to cause energization of the protecting means and to make the time recording means operative for recording the time of such energization.

6. In combination with a means of ingress to and egress from an area, means for controlling such ingress to or egress from the area, means for retaining the controlling means in barring position, time recording means, and means for protecting the area against unwarranted ingress to or egress from the area, the time recording means comprising a circuit including an electromagnetic device which, upon such unwarranted passage into or from the area, causes recording of the time of such passage and then causes the protecting means to initiate an alarm, the record being made and completed before the alarm is initiated.

7. In combination with a means of ingress to an egress from an area, means for controlling such ingress to or egress from the area, means for retaining the controlling means in barring position, time recording means, and means for protecting the area against unwarranted ingress to or egress from the area, the time recording means comprising a circuit including an electromagnetic device which, upon such unwarranted passage into or from the area, causes recording of the time of such passage and then causes the protecting means to initiate an alarm, the record being made and completed before the alarm is initiated, the retaining means, when operated to position to retain the controlling means in barring position, having means active during the same operation to cause energization of the protecting means and to make the time recording means operative for recording the time of such energization.

8. In combination with a means of ingress to and egress from an area, means for controlling such ingress to or egress from the area, means for retaining the controlling means in barring position, time recording means, and means for protecting the area against unwarranted ingress to or egress from the area, the time recording means comprising a circuit including an electromagnetic device which, upon such unwarranted passage into or from the area, causes recording of the time of such passage and then causes the protecting means to initiate an alarm, the record being made and completed before the alarm is initiated, the circuit elements comprising means to re-set the recording means for further recording operation immediately that the alarm has been initiated.

9. In combination, a protective circuit, a lock for retaining closed a portion of an area protected by the circuit, an alarm-creating device, time-recording means, means to energize the circuit, means to operate the time-recording means when the lock is actuated to retaining position, and means for making the alarm-creating device immediately effective to create an alarm when the conductivity of the protective circuit is changed, the lock having means for causing the energization of the effective-making means when the lock is actuated to retaining position, the time-recording means being in circuit to be energized for recording the time of such change of conductivity and having means thereupon to energize the effective-making means.

10. In combination with an enclosure to be guarded against unauthorized entry and exit therefrom, the enclosure having exits therefrom, a closure for one of the exits, an electrical protective circuit disposed about the enclosure and having a portion thereof associated with the closure, means for retaining the closure to prevent passage through the exit guarded thereby, recording means, indicating means, means for energizing the recording means when the retaining means is actuated to effective or ineffective positions, means for energizing the recording means when the protective circuit is interfered with, means for energizing the indicating means when the protective circuit is interfered with, and means to limit actuation of the retaining means to one complete cycle from open position to closed position to open position, the retaining means, when actuated to closed position, causing continuous energization of means to retain the various means electrically energized independently of the subsequent positions of the retaining device or its condition, the actuation limiting means being coin-controlled, the retaining means including a lock bolt, the actuation limiting means including a device for restraining the bolt against movement, the coin-controlled means operating to make the restraining device inoperative.

11. In combination with an enclosure to be guarded against unauthorized entry and exit therefrom, a closure for one of the exits, an electrical protective circuit disposed about the enclosure and having a portion thereof associated with the closure, and means for retaining the closure to prevent passage through the exit guarded thereby, and means separated from the closure-retaining means for retaining the electrical protective circuit continuously energized after the retaining means has been actuated to closed position and independently of the subsequent operation of the retaining device or its condition.

12. In combination with an enclosure to be

guarded against unauthorized entry and exit therefrom, a closure for one of the exits, an electrical protective circuit disposed about the enclosure and having a portion thereof associated with the closure, means for retaining the closure to prevent passage through the exit guarded thereby, time-recording means, means for indicating a change of conductivity of the electrical protective circuit, the protective circuit having means for causing energization of the time recording means, upon change of conductivity of the protective circuit, said indicating means including means to make the indicating means effective, when the electrical protective circuit is operative and then the closure is opened, means for supplying electrical energy for the electrical protective circuit and the conductivity-change indicating means, the retaining means having means for making the supplying means effective for that purpose when but not until the retaining means has been actuated to closure-retaining position and for energizing the time-recording means, the supplying-means-effective-making means remaining effective thereafter independently of the further condition of the closure-retaining means, the energizing means for the time-recording means being made effective when the retaining means is actuated to closure-retaining or closure-releasing position and means to prevent a subsequent actuation of the retaining means to closure-retaining position when the retaining means has once commenced movement to that position unless the preventing means has first been re-set.

13. In combination with an area to be protected and having exits therefrom, means for guarding the exits against unwarranted passage therethrough, means for initiating an alarm upon changing the conductivity of the guarding means, one of the exits having a door, means for locking the door against passage therethrough, the locking means having means to make the alarm-initiating means effective when the locking means is actuated to locking position, means for printing the time when the door was locked and the alarm-initiating means made effective, and means to prevent repeated actuation of the locking means for effecting actuation of the printing means at each actuation of the locking means without first making the alarm-initiating means inoperative.

14. In combination with an area to be protected and having exits therefrom, means for guarding the exits against unwarranted passage therethrough, means for initiating an alarm upon changing the conductivity of the guarding means, one of the exits having a door, means for locking the door against passage therethrough, the locking means having means to make the alarm-initiating means effective when the locking means is actuated to locking position, means for indicating the time when the door was locked and the alarm-initiating means made effective, and coin-controlled means to permit the locking means to be operative for a single continuous period to retain the door locked and thereafter to make the locking means ineffective.

15. In combination with a means of ingress to and egress from an area, means for controlling such ingress to or egress from the area, means for retaining the controlling means in barring position, time-recording means, and means for protecting the area against unwarranted ingress to or egress from the area, the time-recording means, upon such unwarranted passage into or from the area, having means to record the time of such passage and to initiate an alarm so that the

- record is made and completed before the alarm is initiated, the means for initiating the alarm including means to re-set the recording means for a further recording operation when the alarm is initiated, the retaining means, when made operative to retain the controlling means in barring position, having means simultaneously to energize the protecting means and to make the time-recording means operative to record the time of such energization.
16. In combination with a protective circuit for an area to be guarded, means for completing a circuit when the protective circuit is interfered with, a clock device, an alarm circuit, an electromagnet governing the alarm circuit, and an electromagnetic device cooperating with the clock device for indicating particular time periods when the electromagnetic device was energized for that purpose, means to energize the electromagnetic device when the circuit is completed on changing the conductivity of the protective circuit, and means operated by the electromagnetic device when so energized to energize the electromagnet for making the alarm circuit effective.
17. In combination with a protective circuit for an area to be guarded, means for completing a circuit when the conductivity of the protective circuit is changed, a clock device, an alarm circuit, an electromagnetic device cooperating with the clock device for indicating particular time periods when the electromagnetic device was energized for that purpose, an electromagnet governing the alarm circuit and the circuit of the electromagnetic device, means to energize the electromagnetic device when the circuit is completed on changing the conductivity of the protective circuit, and means operated by the electromagnetic device when so energized to energize the electromagnet for making the alarm

circuit effective and to deenergize the electromagnetic device.

18. In combination with a protective circuit for an area to be guarded, means for completing a circuit when the conductivity of the protective circuit is changed, a clock device, an alarm circuit, an electromagnet governing the alarm circuit, a printing member cooperating with the clock device for actuation against the clock device to record particular time periods, an electromagnetic device for actuating the printing means when the electromagnetic device is energized, means for energizing the electromagnetic device when the circuit is completed on change of conductivity of the protective circuit, and means, actuated when the electromagnetic device is energized to drive the printing member against the clock device, to make the alarm circuit effective.

19. In combination with a protective circuit for an area to be guarded, means for completing a circuit when the conductivity of the protective circuit is changed, a clock device, a printing member cooperating with the clock device for actuation against the clock device to record particular time periods, an alarm circuit, an electromagnetic device for actuating the printing means when the electromagnetic device is energized, an electromagnet governing the alarm circuit and the circuit of the electromagnetic device, means for energizing the electromagnetic device when the circuit is completed on change of conductivity of the protective circuit, and means, actuated when the electromagnetic device is energized to drive the printing member against the clock device, to make the alarm circuit effective and to re-set the printing member for a next succeeding printing operation.

BENJAMIN GOLDSSTONE.

CERTIFICATE OF CORRECTION.

Patent No. 2,101,058.

December 7, 1937.

BENJAMIN GOLDSTONE.

It is hereby certified that error appears in the printed specification of the above numbered patent requiring correction as follows: Page 2, first column, line 59, for "form" read forms; and second column, line 17, after "circuit" strike out the comma and insert instead a semicolon; page 6, first column, lines 32, 51 and 70, claims 1, 2 and 3 respectively, after "means" first occurrence, strike out the comma and insert the same after "means" second occurrence; and second column, line 35, claim 5, for "initaite" read initiate; line 36, same claim, after "position" strike out the comma; line 50, claim 6, for the syllable "magnet" read magnetic; line 57, claim 7, for "an" before "egress" read and; page 7, first column, line 66, claim 11, for "havng" read having; and second column, line 10, claim 12, for "time recording means," read time-recording means; line 13, same claim, after "effec-
tive" strike out the comma; line 28, same claim 12, for "closure retain-
ing" read closure-retaining; and after "position" insert a comma; and that
the said Letters Patent should be read with these corrections therein that
the same may conform to the record of the case in the Patent Office.

Signed and sealed this 1st day of March, A. D. 1938.

(Seal)

Henry Van Arsdale,
Acting Commissioner of Patents.
